UNITED STATES PATENT OFFICE.

WILLIAM F. SIEGENER, OF PHILADELPHIA, PENNSYLVANIA, ASSIGNOR TO
HERRMAN DIENELT, OF SAME PLACE.

DESIGN FOR SHELF-PAPER.

SPECIFICATION forming part of Design No. 34,987, dated August 20, 1901.

Application filed July 29, 1901. Serial No. 70,187. Term of patent 3½ years.

To all whom it may concern:

Be it known that I, WILLIAM F. SIEGENER, a citizen of the United States, residing in Philadelphia, Pennsylvania, have invented 5 and produced a certain new and original Design for Shelf-Paper, of which the following is a specification.

My design, which relates to the ornamental border of the shelf-paper, is shown in the accompanying drawing, which represents sufficient of the pattern to illustrate the design, the remainder of the pattern being merely a repetition of what is shown.

The design comprises as its essential features certain rows of perforations and perforated figures adjacent to the scalloped edge of the paper.

1 represents a scalloped edge, and 2 a row of circular perforations inside said edge and following the contour of the scallops. On the opposite side of the border is a line 3 of circular perforations, and between said line and the scalloped edge are a series of figures 4 and 5, forming the balance of the design. 25 The figures 4 alternate with the figures 5, the

former consisting of a central circular perforation and a series of wedge-shaped perforations projecting toward said central perforation, while the latter consists of a central circular perforation and a series of wedge-shaped perforations on four sides of the same, said central perforation and the wedge-shaped perforations being surrounded by a series of smaller circular perforations, which form an approximate square. The figures 5 are disposed in line with the scallops of the edge. 30 35

Having thus described my invention, I claim and desire to secure by Letters Patent—

The design for shelf-paper, substantially as 40 described and as shown in the accompanying drawing.

In testimony whereof I have signed my name to this specification in the presence of two subscribing witnesses.

WM. F. SIEGENER.
